UNITED STATES PATENT OFFICE.

MAURITZ C. INDAHL, OF PHILADELPHIA, PENNSYLVANIA.

DRIVING MECHANISM.

1,308,634.

Specification of Letters Patent.

Patented July 1, 1919.

Application filed August 24, 1916. Serial No. 116,683.

To all whom it may concern:

Be it known that I, MAURITZ C. INDAHL, a citizen of the United States, residing at Philadelphia, in the county of Philadelphia 5 and State of Pennsylvania, have invented certain new and useful Improvements in Driving Mechanism; and I do hereby declare the following to be a full, clear, and exact description thereof, reference being 10 had to the accompanying drawings, forming part of this specification.

This invention relates to driving mechanism wherein a pair of driven members are adapted to be driven at differential speeds, 15 and the primary object in view is the provision of an improved and novel means for arbitrarily causing said members to be positively driven at variable ratios of differentiation.

With the above and other objects in view the invention consists in certain novel constructions, combinations and arrangements 20 of parts hereinafter described in a preferred form and pointed out in the claims at the 25 end of the specification.

In the drawings:—

Figure 1 is a top plan view of one type of balanced differential gearing provided with the present improvements, the top wall of 30 the gear box or casing being partially broken away to show the interior construction.

Fig. 2 is a horizontal longitudinal sectional view of the same.

Fig. 3 is a rear elevation of Fig. 1 with the 35 rear wall of the gear box partially broken away.

Fig. 4 is a detailed vertical sectional view taken on the line 4—4 of Fig. 2.

Fig. 5 is a detailed vertical sectional view 40 taken on the line 5—5 of Fig. 1.

Fig. 6 is a front elevation of the gear box.

Fig. 7 is a side elevation of the same.

Fig. 8 is a rear elevation.

Fig. 9 is a diagrammatic plan view of the 45 front and rear wheels of a motor driven vehicle illustrating the present improved differential mechanism controlled by steering gear of one type.

Fig. 10 is a diagrammatic side elevation of 50 the arrangement illustrated in Fig. 9.

Fig. 11 is another diagrammatic plan view illustrating the differential mechanism controlled by a different type of steering gear.

Fig. 12 is a diagrammatic side elevation of 55 the arrangement illustrated in Fig. 11.

Fig. 13 is a detail view hereinafter more fully described.

Like characters of reference in the several figures indicate the same parts. 60

Although it will be understood that the invention is capable of broad application and many different uses, its utility is strikingly illustrated when employed in connection with differential gears for motor driven 65 vehicles, such as automobiles, and, hence, for convenience, the present description will be confined to this particular use of the invention. The purpose of a differential gear as commonly employed, by an automobile, 70 is to divide the power from the motor equally to the two driven members of a divided wheel axle, and in such manner that the relative speeds of the two driven members may be varied by outside conditions without 75 affecting the motor. Thus, in effect, a differential gear is a means for permitting acceleration in speed of one driven member accompanied by a reduction in speed of the other driven member, the reduction in speed 80 in some instances being proportionate to the acceleration.

According to the present invention, two members adapted to be driven at differential speeds, as in the above set forth manner, 85 may be positively driven at variable ratios of differentiation arbitrarily selected, for example, at the will of the driver of a motor car. This variation of differential action may be advantageously utilized for steering 90 purposes, since the driver will be enabled by proper manipulation to positively accelerate the speed of one driven member and concurrently to positively diminish the speed of the other driven member. As this acceleration 95 and diminution in speed of the driven members at the opposite sides of a motor car can be effected at any desired ratio of differentiation within the limits of differential action, it is obvious that the car can quickly 100 be turned on a long or short radius determined solely by the ratio of differentiation at which the driven members are driven. In this way, steering may in some instances be effected by the power of the motor itself 105 and with little effort on the part of the driver of the car. If the driven members support the rear driving wheels and steering is effected through front steering wheels, as is common in automobiles, the principle 110 of my invention may advantageously be utilized by controlling the ratio of differen-

tiated speeds at which the driven members are driven directly by the steering gear. By this, the steering operation will be greatly assisted as the rear wheels will differentiate in speed at ratios directly controlled by the degree of manipulation of the steering gear, or in other words, the amount of turning radius of the automobile. The perfect control which the driver has over the differential action will also enable him to positively prevent one driven member from accelerating at a dangerous speed, such as to cause skidding.

The differential gearing utilized in the present embodiment of the invention and illustrated in the accompanying drawings is one well known type of balanced differential gearing employed in motor cars wherein the power from the motor is normally equally distributed to the two driven members of a divided wheel axle or shaft. In the form shown, the differential gearing is of the bevel gear type and is inclosed within the stationary gear box or casing. This gear box is provided with suitable sleeve bearings 2, 3, located respectively in the right and left hand walls of the box and in which are journaled the right and left hand driven members 4, 5, of a divided wheel axle or shaft. It will be understood that, in the present embodiment, each driven member is adapted at its outer end to support and drive a wheel. A shell 6 is provided at its right and left hand ends with sleeves 7, 8, the latter being journaled for rotation on the driven members 4, 5, and also within right and left hand bearing sleeves 9, 10, supported by the gear box 1, as shown in Fig. 2. This rotary shell 6 is provided with a large worm gear 11 in mesh with a worm 12 carried by the end of the driving member or shaft 13 which is suitably journaled in the upper wall of the gear box, as shown in Fig. 7. In the present embodiment of the invention, the shaft 13 is the Cardan or transmission shaft of a motor car. Fixed respectively to the right and left hand driven members 4, 5 and located within the rotary shell 6 are the right and left hand bevel drive gears 14, 15. Journaled for rotation on fixed stud shafts 16 mounted within shell 6 are the bevel differential pinions 17, the latter being in the present embodiment four in number, as shown in Fig. 4. These pinions 17 are in mesh with the right and left hand gears 14 and 15. The operation of differential gearing of this type is well known in the art, it being sufficient to state that the several pinions 17 serve normally to distribute power from the rotary shell 6 equally to the respective driven members 4, 5, through the intermediary gears 14, 15, and also permit one driven member to revolve with a greater speed than the normal drive accompanied by

a proportional reduction in speed of the other driven member, and this, without in any way disturbing the Cardan or transmission shaft 13.

The present invention has particular reference to the means for arbitrarily causing the driven members 4, 5 to be driven at variable ratios of differentiation, or, in other words, by the present invention, the speed of one driven member may be accelerated through manual manipulation and concurrently the speed of the other driven member may be diminished. As the speeds of both driven members are under the manual control of the driver of the car, it is obvious that they may be positively driven at any desired predetermined ratios of differentiated speeds, for example, one driven member can be accelerated to any predetermined extent within the limits of the capacity for differentiation and concurrently the speed of the other driven member can be proportionately diminished. The means for applying this principle in the operation of a driving mechanism will now be described.

Fixed respectively to the driven members 4, 5 are bevel gears 18, 19, (Fig. 2). These gears are respectively in mesh with bevel pinions 20, 21, on shafts 22, 23, disposed at right angles to the driven members 4, 5. The shafts 22, 23, are journaled for rotation in bearings 24, 25 formed in the side walls of the gear box 1 and project into a chamber 26 located at the inner end of said gear box and inclosed by extensions of the walls thereof. Within the chamber 26 and fixed respectively to the projecting ends of shafts 22, 23, are friction disks 27, 28. Extending longitudinally of the chamber 26 is a fixed shaft 29 on which is slidably and rockably mounted a yoke 30. The lower arms 31, 32 of said yoke are provided with journals as shown in Fig. 3, supporting the spindle 33 of a roller 34. Roller 34 is provided with opposite engaging peripheral surfaces 35, 36, adapted to be thrown into frictional contact with the respective friction disks 27, 28, as will hereinafter appear. Above the fixed shaft 29 the yoke 30 is formed with a rack 37 in mesh with a pinion 38 on the steering shaft 39, the latter extending transversely within chamber 26 and being supported by suitable bearings 40, 41, as shown in Fig. 5.

From the foregoing description, it is obvious that by rotating steering shaft 39, yoke 30 is shifted longitudinally along fixed shaft 29, and, as a result, the engaging surfaces 35, 36 of the roller 34 are moved across the faces of the disks 27, 28. Assuming that yoke 30 is shifted toward the right of Fig. 3, the engaging surface 35 of disk 34 is moved toward the center of friction disk 27 and engaging surface 36 is moved 130

toward the periphery of disk 28. Accordingly, if the said engaging surfaces 35, 36 are brought into frictional contact with the disks 27, 28, the driven members 4, 5 will be positively driven at differential speeds, the ratio of differentiation depending upon the distance which engaging surface 35 has been moved toward the center of disk 27 and, concurrently, the distance which engaging surface 36 has been moved toward the periphery of disk 28. When the parts are in this position, the speed of driven member 5 is diminished and the speed of driven member 4 accelerated. By shifting yoke 30 reversely, *i. e.*, toward the left of Fig. 3, the speed of driven member 5 may be accelerated and that of driven member 4 diminished. It will be noted that the above described positive drive of the members, 4, 5, at variable ratios of differentiated speeds is effected by simply turning the steering shaft 39 in one direction or the other, and by bringing the engaging surfaces of the roller 34 into frictional contact with the disks. As soon as such frictional contact is established, the members 4, 5, are connected together and positively driven at the predetermined differentiated speeds, the roller 34 forming a governing member for positively effecting this result. The ratio of differentiation at which the members 4, 5 are driven may be any ratio within the limits of differential action of the gearing, it being possible to drive the members 4, 5 at a great difference in speed, for example, when turning the motor car around a sharp curve, or at a very small difference in speed when the amount of steering to be done is relatively slight.

40 The longitudinal adjustment of yoke 30 to vary the ratio of differentiation of the driven members may be effected, while the engaging surfaces 35, 36 are in contact with disks 27, 28, or said engaging surfaces may be moved out of contact with said disks and the longitudinal adjustment then effected. The mechanism for moving the engaging surfaces of the roller 34 into and out of frictional contact with disks 27, 28 will now be described: Pivoted at 42 to the top plate of the casing is a lever arm 43, the latter supporting substantially midway its ends a roller 44 (Figs. 1 and 5). Roller 44 is adapted to bear against the opposing face of the longitudinal bar 45 (Figs. 1, 3 and 5) of an open frame 46 supported by the yoke 30 above the fixed shaft 29. A rod 48, which, in the present embodiment, is adapted to have an operative connection with a foot pedal of any preferred construction, and indicated diagrammatically by the reference character 48^a in Figs. 11 and 12, is slidably journaled in a bearing formed in the front wall of the chamber 26. The inner end of said rod 48 is provided with a

yoke 47 adapted to embrace the yoke 49^a of an alined rod 49^b slidably journaled in the rear wall of the chamber 26 (Fig. 13). An adjustable head 49 on rod 49^b and bearing against the outer face of the rear wall of the chamber limits the movement of rod 49^b. Yoke 47 is provided with circular openings and yoke 49^a with slotted openings, as shown in Fig. 13, and a pin 47^a is passed through the openings in the respective yokes and the free end of bar 45, whereby the latter is pivoted to the yokes between the two alined shafts 48, 49^b. A spring 50 encircling rod 49^b and interposed between the rear chamber wall and yoke 49^a is adapted to yieldingly swing the lever arm 43 in a direction to force roller 44 into contact with bar 45 and thereby rock the yoke 30 on its supporting shaft 29 to bring the engaging surfaces 35, 36 of the roller into frictional contact with disks 27, 28. When operating rod 48 is moved in one direction so as to compress the spring 50, arm 43 will be swung to move roller 44 away from bar 45. The arms 31 and 32 of the yoke are so disposed as to swing the roller 34 away from the disks 27, 28, when this movement of rod 48 is effected. The bar 45 is provided with a notch 51 in which the roller 44 is adapted to enter when the yoke is in neutral position, *i. e.*, when the driven members 4, 5 are being driven at equalized speeds, in the normal operation of the motor car. The engagement of the roller 44 with the notch 51 permits the yoke 30 to swing roller 34 out of engagement with the disks 27, 28, and the differential gearing hereinbefore described is thus free to act and permit automatic acceleration of one driven member accompanied by a proportionately diminished speed of the other driven member in the ordinary way.

By reason of the slots in yoke 49^a, rod 48 may be shifted relatively to rod 49^b in the reverse direction to that previously described. This movement will, of course, be accomplished by a reverse movement of the foot pedal 48^a, and when so done, effects shifting of the yoke 30 to bring the engaging surfaces 35, 36 into contact with the disks 27, 28, even when the yoke 30 is in neutral position, *i. e.*, with the roller 44 in notch 51. Thus, if one of the wheels begins to slip when the differential gearing is free to act, both wheels may be driven positively at equalized speeds.

Figs. 9 to 12, inclusive, are diagrammatic representations of applications of the invention to different types of steering gear employed in automobiles. Referring particularly to Figs. 9 and 10, the rear driven wheels of an automobile are indicated at 52, said wheels being supported by the driven members 4, 5 of the present improved driving mechanism. The drive shaft 13 from the motor M enters the casing 1, and drives

the shell of the differential gearing, as heretofore explained. Pivoted to turn in vertical axes on the front axle 53 are the front steering wheels 54, the latter having the usual steering knuckles 55 connected by a transverse bar 56. One of said knuckles has a steering arm 57 pivoted at its free end to a link 58 jointed to an arm 58' fixed on a small shaft 59. The link is operated to move 10 the steering arm and turn the front wheels by turning the shaft 59 and the latter operation is effected by the usual steering wheel 60 on a steering post 61 having a worm 62 in mesh with a worm gear 63 fixed 15 on the shaft 59. Also fixed on shaft 59 is a bevel pinion 64 in mesh with a bevel pinion 65 on a Cardan shaft 66, connected with the shaft 39 for operating the governing member 34.

20 With this arrangement, turning of the wheel 60 to the left, will through the steering gear turn the front wheels to the left. The motion of the shaft 59, in effecting this movement, is communicated to shaft 39, 25 which, as has previously been stated, shifts the governing member. Accordingly, the latter will be shifted toward the right side of the machine, bringing the peripheral surface 35 of the governing member toward the 30 periphery of disk 27 and peripheral surface 36 toward the center of disk 28. This movement of the governing member will be effective to positively drive the left hand rear wheel at a diminished speed and the speed 35 of the right hand rear wheel will be proportionately accelerated, thereby greatly assisting in the steering operation. The amount of differentiation at which the rear wheels may be driven is dependent upon the 40 degree of movement of the steering wheel 60; in other words, the ratio of differential action is directly proportionate to the turning radius of the vehicle. On turning the front steering wheels to the right, the action 45 of the governing member is the reverse of that just described.

In the arrangement shown in Figs. 11 and 12, the operation of the governing member is the same. A different type of steering 50 gear is employed however. One of the steering knuckles 67 of the front wheels is elongated beyond the connecting bar 68, and is pivoted to a steering rod 69. The latter in turn is pivoted to a link 70 on a longitudinal shaft 71, connected by a universal joint with the shaft 39. The steering post 61 is provided with a worm 72 meshing with a worm gear 73 on shaft 71, the turning movement imparted to the shaft 71 by this intermediate 55 gear on turning the steering wheel 60, acts to operate the link 70 to shift knuckle 67 and effect steering. Simultaneously, the governing member controlling differential action is shifted by the turning movement 60 of shaft 71.

What is claimed is:—

1. The combination of a driving member, a pair of members driven thereby through mechanism permitting said driven members to differentiate in speed, and means independent of the driving member for arbitrarily causing said members to be driven positively at variable ratios of differentiation. 70

2. The combination with a driving member, a pair of driven members and means for permitting acceleration in speed of one of said driven members accompanied by a proportionately diminished speed of the other driven member, of means independent of the driving members for arbitrarily causing said members to be driven positively at 75 variable ratios of differentiation. 80

3. The combination of a pair of driven members, a driving member, gearing connections between said driven members and the driving member for driving said driven members normally at equalized speeds and also permitting an acceleration in speed of one of said driven members accompanied by a proportionately diminished speed of the other driven member, and means independent of the driving member for arbitrarily causing said driven members to be driven positively at variable ratios of differentiation. 90 95

4. The combination of a pair of driven members, a driving member, differential gearing interposed between the driven members and the driving member for permitting acceleration in speed of one of said driven members accompanied by a proportionately diminished speed of the other driven member, and means independent of the driving member for arbitrarily causing said driven members to be driven positively at variable 100 105 ratios of differentiation.

5. The combination of a driving member, a pair of members driven thereby through mechanism permitting said driven members to differentiate in speed, and manually operated controlling means for arbitrarily causing said driven members to be driven one by the other positively at variable ratios of differentiation. 110

6. The combination with a pair of driven members and means for permitting acceleration in speed of one of said driven members accompanied by a proportionately diminished speed of the other driven member, of a manually operated controlling means for 115 120 arbitrarily causing said driven members to be driven one by the other positively at variable ratios of differentiation.

7. The combination of a pair of driven members, a driving member, gearing connections between said driven members and the driving member for driving said driven members normally at equalized speeds and also permitting an acceleration in speed of one of said driven members accompanied by 125 130

- 5 a proportionately diminished speed of the other driven member, and a manually operated controlling means for arbitrarily causing said driven members to be driven one by the other positively at variable ratios of differentiation. 13. The combination of a pair of driven members adapted to be driven at differential speeds, a governing member for causing said driven members to differentiate at a predetermined ratio normally in inoperative relation thereto, means for manually adjusting said governing member to vary the predetermined ratio, and spring means for connecting said governing member with the driven members. 70
- 10 8. The combination of a pair of driven members, a driving member, differential gearing interposed between the driven members and the driving member for permitting acceleration in speed of one of said driven members accompanied by a proportionately diminished speed of the other driven member, and a manually operated controlling means for arbitrarily causing said driven members to be driven one by the other positively at variable ratios of differentiation. 14. The combination of a pair of driven members, a driving member, gearing connections between said driven members and the driving member for driving said driven members normally at equalized speeds and also permitting an acceleration in speed of one of said driven members accompanied by a proportionately diminished speed of the other driven member, a governing member for causing said driven members to differentiate at a predetermined ratio normally in inoperative relation thereto, means for manually adjusting said governing member to vary the predetermined ratio, and spring means for connecting said governing member with the driven members. 75
- 15 9. The combination with a pair of driven members and means for permitting acceleration in speed of one of said members accompanied by a proportionately diminished speed of the other driven member, of a governing member for causing said driven members to differentiate at a predetermined ratio, and means for manually effecting an operative engagement or disengagement of said governing member and the driven members. 15. The combination of a pair of driven members adapted to be driven at differential speeds, a governing member for causing said driven members to differentiate at a predetermined ratio normally in inoperative relation thereto, means for manually adjusting said governing member to vary the predetermined ratio, and means for automatically connecting said governing member with the driven members when adjusted to drive the latter at a predetermined ratio of differentiation. 80
- 20 10. The combination of a pair of driven members, a driving member, gearing connections between said driven members and the driving member for driving said driven members normally at equalized speeds and also permitting an acceleration in speed of one of said driven members accompanied by a proportionately diminished speed of the other driven member, a governing member for causing said driven members to differentiate at a predetermined ratio, and means 90
- 25 for manually effecting an operative engagement or disengagement of said governing member and the driven members. 16. The combination with a pair of driven members adapted to be driven at differential speeds, a governing member for causing said driven members to differentiate at a predetermined ratio, means for manually adjusting said governing member to vary the predetermined ratio, and also to permit the driven members to be driven at equalized speeds, and means for automatically connecting the governing member with the driven members when adjusted to drive the latter at a predetermined ratio of differentiation and for disconnecting said governing member from the driven members when the latter are driven at equalized speeds. 95
- 30 11. The combination of a pair of driven members, a driving member, differential gearing interposed between the driven members and the driving member for permitting acceleration in speed of one of said driven members accompanied by a proportionately diminished speed of the other driven member, a governing member for causing said driven members to differentiate at a predetermined ratio, and means for manually effecting an operative engagement or disengagement of said governing member and the driven members. 17. The combination of a pair of driven members, a driving member, gearing connections between said driven members and the driving member for driving said driven members normally at said equalized speeds and also permitting an acceleration in speed of one of said driven members accompanied by a proportionately diminished speed of the other driven member, a governing member for causing said driven members to differentiate at a predetermined ratio, means 100

- 6
 for manually adjusting said governing member to vary the predetermined ratio, and also to permit the driven members to be driven at equalized speeds, and means for 5 automatically connecting the governing member with the driven members when adjusted to drive the latter at a predetermined ratio of differentiation and for disconnecting said governing member from the driven members when the latter are driven at equalized speeds.
- 10 18. The combination of a drive shaft, a pair of rear wheels driven by said drive shaft through mechanism permitting said rear wheels to differentiate in speed, a pair of front steering wheels, manually operated steering gear for turning the latter, and means responsive to manual manipulation of the steering gear for arbitrarily causing said 20 rear wheels to be driven positively at variable ratios of differentiation.
- 15 19. The combination with a pair of rear driven wheels and means for permitting acceleration in speed of one of said driven wheels accompanied by a proportionately diminished speed of the other driven wheel, of a pair of front steering wheels, manually operated steering gear for turning the latter, and means responsive to manual manipulation of the steering gear for arbitrarily causing said 30 rear driven wheels to be driven positively at variable ratios of differentiation.
- 20 20. The combination with a pair of rear driven wheels, a drive shaft, gearing connections between said driven wheels and drive shaft for driving said wheels normally at equalized speeds and also permitting an acceleration in speed of one of said rear 35 wheels accompanied by a proportionately diminished speed of the other rear wheel, a governing member for causing said rear wheels to differentiate at a predetermined ratio, a pair of front steering wheels, 40 manually-operated steering gear for turning the latter, and means responsive to manual manipulation of the steering gear for adjusting said governing member to vary the predetermined ratio.
- 45 21. The combination of a pair of driven members, a drive member, differential gearing between the driven members, and gearing positively connecting the driven members independently of the drive member 50 so that one of said members will be driven at a definite ratio to the speed of the other driven member.
- 55 22. The combination of a pair of driven members, a drive member, differential gearing between the driven members, and gearing including a governing member positively connecting the driven members independently of the drive member, so that the speed of one of the driven members will 60 bear a definite ratio of the speed of the other
- driven member for each position of the governor.
23. The combination of a pair of driven members, a drive member, differential gearing between the driven members, and gearing including a governing member positively connecting the driven members independently of the drive member so that the speed of one of the driven members will bear a definite ratio to the speed of the other 70 driven member for each position of the governor, and means for moving the governor to any of a plurality of positions.
- 75 24. The combination of a pair of driven members, a drive member, differential gearing between the driven members, a friction wheel driven by each driven member, a means for causing the friction wheels to drive one of the driven members by power derived from the other driven member. 80
- 85 25. The combination of a pair of driven members, a drive member, differential gearing between the driven members, a friction wheel driven by each driven member, and means for causing the friction wheels to drive one of the driven members by power derived from the other and at a definite ratio with respect to the speed of the other driven member.
- 90 26. The combination of a pair of driven members, a drive member, differential gearing between the driven members, a friction wheel driven by each driven member, and means for causing the friction wheels to drive one of the driven members by power derived from the other and at any one of a 95 plurality of ratios with respect to the speed of the other driven member.
- 100 27. The combination with a pair of driven members, a drive member, differential gearing between the driven members, and gearing adapted to be thrown into and out of connection with the driven members for establishing at will a positive drive between said driven members, whereby either may be 105 controlled by the other.
- 110 28. The combination with a pair of driven members, a drive member, differential gearing between the driven members, and gearing adapted to be thrown into and out of connection with the driven members for establishing at will a positive drive between 115 said driven members at any one of a plurality of different ratios.
- 120 29. In a motor driven four-wheeled vehicle, drive mechanism for the rear wheels including a differential gear, steering means for the front wheels, and means controlled by said steering means for positively connecting said rear wheels so as to assist in the 125 steering by the front wheels.
- 130 30. The combination of a pair of driven members, a drive member, differential gearing between the driven members and through which the power of the drive mem-

ber is communicated thereto, and manually controlled gearing connecting the driven members and operating to transfer a portion of the power delivered to one driven member through the differential, to be transferred to the other driven member.

31. In a motor driven vehicle, drive mechanism therefor, including a differential

gearing, steering means for the vehicle, and means controlled by said steering means 10 whereby a portion of the power delivered through one side of the differential will be transferred to the other side thereof for effecting a desired ratio of differentiation.

MAURITZ C. INDAHL.
